UNITED STATES PATENT OFFICE

GUSTAVUS A. PFEIFFER, OF NEW YORK, N. Y.

MULTIPLE-COMPARTMENT CONTAINER

Application filed September 25, 1929. Serial No. 394,938.

This invention relates to face powder boxes in general and more especially to multiple compartment face powder boxes.

Among the objects of the present invention it is aimed to provide an improved multiple compartment face powder box in which a plurality of separated portions of powder can be carried.

It is still a further object of the present invention to provide an improved multiple compartment face powder box having one compartment for a day face powder and another compartment for a night face powder, each of which compartments is readily accessible without disturbing the contents of the other compartment.

Among the objects of the present invention it is also aimed to provide a multiple compartment face powder box having a compartment for a day face powder and another compartment for a night face powder, and which compartments can be readily filled and sealed one against the other with a minimum number of operations and so sealed with a minimum danger of spilling.

These and other features, capabilities and advantages of the invention will appear from the subjoined detail description of the specific embodiments thereof illustrated in the accompanying drawings in which

Fig. 1 is a transverse section of a box made according to one embodiment;

Fig. 2 is a bottom plan view of the same;

Fig. 3 is a transverse section of the bottom compartment portion of this embodiment;

Fig. 4 is a transverse section of the two parts of the box containing the upper compartment and cover for the lower compartment of this embodiment;

Fig. 5 is a transverse section of the cover for the upper compartment of this embodiment;

Fig. 6 is a transverse section of another embodiment; and

Fig. 7 is a transverse section of the two main parts associated with the lower compartment of this second embodiment.

In the embodiment illustrated in Figs. 1 to 5 inclusive, there is provided a bottom portion A containing the lower compart-

ment, an intermediate portion B containing the cover for the lower compartment and the upper compartment, and the cover portion C.

In Fig. 3, the lower portion A is illustrated as provided with the shoulder portion 1, an annular wall portion 2 to which is secured a destructible seal 3, and a base portion 4 which is preferably composed of two sheet members 5 and 6, the sheet member 6 having a circular opening 7 and the sheet member 5 having an opening 8 of greater diameter than the opening 7 so that a flange portion 9 is formed by the annular portion of the layer 6 around the opening 7. This lower portion A is initially prepared as aforesaid with the opening 7 formed therein and then supplied to the filling station where the powder, the night powder in the present instance, is poured through this opening 7 in the base 4, and thereupon the closure member 10 having the flange 11 registering with the flange 9, and then another layer such as a paster or label 12 pasted or otherwise permanently secured to the lower face of the closure member 10 and base 4 to seal the closure member 10 in place.

The intermediate portion B is provided with an annular wall 13 corresponding in peripheral extent with the shoulder 1 and having an inner diameter substantially corresponding with the outer diameter of the annular wall 2 so that the wall 13 may receive the wall 2 of the lower portion A. The wall 13 has a plane intermediate wall portion 14 secured thereto to form the bottom or base of the upper compartment. To this base 14 and inside the wall 13 there is secured the annular wall 15, leaving a shoulder at 16 between the walls 13 and 15. The wall member 13 is preferably of sufficient extent so that when its outer free edge engages the shoulder 1, the base portion 14 will be spaced from the destructible seal 3 as indicated in Fig. 1.

To the inner face of the wall 15 there is secured the outer face of the annular wall 18 to which is secured the destructible seal 19. The annular wall 18 and destructible seal 19 are initially prepared and supplied to the filling station where they are filled with the

desired powder, in the present instance the day face powder, and thereupon the outer surface of the wall 18 has formed thereon a suitable adhesive substance whereupon the intermediate portion B is forced down with the inner face of the wall 15 sliding on the outer face of the wall 18 until it is driven home to the position indicated in Fig. 1 where the destructible seal 19 is disposed at the level of the free edge 20 of the wall 15.

10 To the wall member 15 there is attached the cover portion C which consists of the annular wall 21 and base portion 22, the annular wall 21 having an inner diameter sufficient to clear the inner face of the wall 15. When the inner edge 23 of the annular wall 21 engages the shoulder 16 of the wall 13 as indicated in Fig. 1, the lower face 24 of the base 22 will be spaced from the seal 19 as indicated in Fig. 1, 15 the wall member 21 being of sufficient length to clear the upper edge 20 of the annular wall 15.

With a multiple compartment face powder box constructed as aforesaid, the container portions for the face powder can be separately filled and two cover members provided for the two container portions which may be spaced, in their final assembly from the upper destructible seal of the container portions, and yet when the cover members are in place on both container portions, a unitary structure is provided.

The spaces formed above the seals 3 and 19 serve several important functions. In the first place, due to the fact that these face powder boxes are used on ornamental dressing tables and the like, face powder box manufacturers have vied with one another in producing boxes that are highly artistic both in shape and color. When the spaces formed above the seals 3 and 19 are provided, the shape of the box need not be determined by the quantity of powder contained therein, the seal properly anchoring the powder portion in place irrespective of the dimension of the spaces formed above the seals, and the spaces therefore be determined only according to the design of box desired. In the next place, after the seals are broken and the boxes have come into use, the provision of a space above the upper level of the surface of the powder is highly desirable to prevent the powder being squirted through the sides of the cover when pressing the cover into place, the spaces providing air cushion chambers for the air extruded in such closing action which will be sufficient to permit the air extruded to gradually leak out without unduly agitating the powder and carrying it along during such extruding action.

With a multiple compartment face powder box made as aforesaid, it is also apparent that there is little danger of spilling the powder when either face powder container is in use. When the lower face powder

70 container is being used, the upper face powder container forms an intimate part of the cover and the unused upper face powder container remains undisturbed when the intermediate portion B forming the cover for the lower face powder container is removed, and in turn, when the upper face powder container is being used, the lower face powder container remains undisturbed beneath the upper face powder container while the cover C is removed.

75 In the embodiment illustrated in Figs. 6 and 7, the intermediate portion B' is identical with the intermediate portion B of the embodiment illustrated in Figs. 1 and 5, and similarly, the cover portion C' is identical with the cover portion C of the embodiment illustrated in Figs. 1 to 5. Merely the portion A' differs from the portion A of the embodiment illustrated in Figs. 1 to 5 and therefore the portion A' alone will be described in detail.

80 The portion A' of the embodiment illustrated in Figs. 6 and 7 comprises an annular wall 25 secured to the inner face of the flange 26 of the base portion 27. To the inner face of the wall 25 is secured the outer face of the annular wall 28 of the container portion having secured thereto the seal 29. The annular wall 28 and seal 29, as illustrated in Fig. 7, is supplied to the filling station where it is filled with the desired face powder, the night powder in the present instance. Thereupon, the base portion A' is inverted as illustrated in Fig. 7, and after having a suitable adhesive substance secured to the outer face of the wall 28, such base portion A' is pressed down until the free edge 30 of the wall 28 engages the base portion 27, when the seal 29 will be substantially at the level of the free edge 31 of the annular wall 25. The inner diameter of the wall 13' of the intermediate portion B' will be sufficient to clear the outer face of the wall 25 so that the wall 13' can slide over the wall 25 and rest on the flange 26. The height of the wall 13' as compared to the wall 25 is sufficient so that a space will be formed between the seal 29 and the base 14' of the intermediate portion B'.

5 container having a seal and a cover for the lower powder container, and an upper cover for the upper powder container, the cover of the intermediate portion being spaced from the lower container, and the upper cover being spaced from the upper container.

10 2. In a multiple compartment face powder box, the combination with a lower powder container having a shoulder formed along its lower edge, of an intermediate portion composed of an upper powder container and a cover for the lower powder container, the cover of the intermediate portion in closed position receiving the lower powder container and resting on the shoulder of the lower powder container, the upper powder container having a peripheral shoulder, and an upper cover in closed position receiving the upper powder container and resting on 20 the shoulder of the upper powder container.

15 3. In a multiple compartment face powder box, the combination with a lower powder container having a destructible seal forming the upper closed surface thereof and having an outer peripheral shoulder along its lower edge, an intermediate portion composed of an upper powder container and a cover portion for the lower powder container, the upper powder container having a destructible seal forming the upper closing wall thereof and having an annular shoulder along its lower peripheral edge, and an upper cover for the upper powder container, the edge of the cover member of the intermediate portion 30 resting on the shoulder of the lower powder container and the edge of the upper cover member resting on the shoulder of the upper powder container to form spaces above the destructible seals of the powder containers.

35 40 4. In a multiple compartment face powder box, the combination with a lower powder container having a seal forming the upper closure member thereof, an outer shoulder along its lower peripheral edge, there being a supply opening in the bottom thereof, and a permanent seal for said supply opening after the powder has been received, of an intermediate portion having an upper powder container and a cover member for a lower 45 powder container, the upper powder container having a seal formed in its upper closure member and a shoulder along its lower peripheral edge, and an upper cover for the upper powder container, the lower edge of the cover member of the intermediate portion engaging the shoulder of the lower powder container and the lower edge of the upper cover member engaging the shoulder of the upper powder container to form spaces 50 above the seals of said powder containers.

55 60 GUSTAVUS A. PFEIFFER.
